CLAIM

The ornamental design for shelf element, as shown and described.

DESCRIPTION

FIG. 1 is an elevated front view of a shelf element in accordance with a first embodiment of the present invention; FIG. 2 is an elevated front-right perspective view thereof, with the front-left perspective view being a mirror image thereof;

FIG. 3 is an elevated rear perspective view thereof;

FIG. 4 is a top plan view thereof; and,

FIG. 5 is a bottom plan view thereof.

The broken lines included in the drawings show features that form no part of the claimed design.
